OIL BURNER TOBACCO CURER

Sidney C. Barker, Mount Airy, N. C.

Application February 13, 1953, Serial No. 336,752

1 Claim. (Cl. 126—59.5)

This invention relates to heat providing elements for tobacco curing barns and other enclosures and in particular a burner housing mounted in one end of a header with deflecting baffles adjustably mounted above the burner housing and adjoining section of the header.

The purpose of this invention is to provide an adjustable deflecting element above a heat supplying unit whereby heat traveling upwardly from the unit may be deflected to different sections of an enclosure in which the device is positioned.

Various attempts have been made to evenly distribute heat throughout the interior of a tobacco barn, and at the same time provide sufficient circulation for curing tobacco, however, it is difficult to incorporate a burner, and particularly an oil burner in a heating system without heat being concentrated in an area around the burner. With this thought in mind this invention contemplates a burner unit having deflecting baffles adjustably mounted in the path of air traveling upwardly therefrom whereby the heated air is directed to different sections of an enclosure in which the device is positioned.

The object of this invention is, therefore, to provide means for mounting deflecting baffles above a heating unit whereby the position of the baffles is readily adjustable and whereby heat from the unit may be directed to one section of an enclosure for a certain period of time, and to different sections for following periods of time.

Another object of the invention is to provide a heating unit with deflecting baffles adjustably mounted thereon in which the unit may readily be installed in one end of a header in a tobacco barn or the like.

A further object of the invention is to provide a heating unit having deflecting baffles adjustably mounted thereon for use in tobacco curing, in which the unit is of a simple and economical construction.

With these and other objects and advantages in view the invention embodies a housing having an oil burner with a down draft flue extended therefrom and having a deflecting baffle carried by the upper surface, and an additional deflecting baffle with means for mounting the said additional deflecting baffle on an adjoining section of a header to which the burner housing is connected.

Other features and advantages of the invention will appear from the following description taken in connection with the drawings, wherein:

Figure 1 is a plan view of the improved heating unit with part of a baffle over the burner housing broken away.

Figure 2 is a side elevational view of the unit shown in Fig. 1 showing the deflecting baffles in horizontal positions in full lines and in inclined positions in dotted lines.

Figure 3 is a cross section through the header, looking toward the heating unit and showing the baffle carried by the header in a horizontal position in full lines and in inclined positions in dotted lines.

Figure 4 is a longitudinal section through the burner housing showing the housing attached to an end of a

2

header with parts broken away, said section being taken on line 4—4 of Fig. 1.

Figure 5 is a plan view showing the burner on an enlarged scale, the base of the housing being broken away.

5 Figure 6 is a detail showing the fuel disc of the burner.

Referring now to the drawings wherein like reference characters denote corresponding parts the improved tobacco curing oil burner of this invention includes a down draft oil burner having a cup shaped casing 10 with a fuel

10 disc 11 therein positioned below a down draft flue 12 and mounted in a well 13 on a base 14 of a housing having side walls 15 and 16, end walls 17 and 18 and a cover 19, and the housing which is provided with a deflector 20 is mounted in the end of a header 21 above which a baffle 22, mounted on a shaft 23, is supported with legs 24 and 25. The header 21 is adapted to extend to a stack or chimney whereby the circulation of air upwardly through the stack pulls air downwardly through the flue 12.

20 As illustrated in Fig. 4 the base 14, which is supported on legs 26 is provided with an annular boss 27 in which the well 13 is positioned and the casing 10, which is located in the well is provided with a frustro conical shaped inner surface 28. The upper edge of the wall of the cas-

25 ing 10 is provided with an annular groove 29 in which overflow fuel may accumulate and fuel from the groove 29 is returned to the supply through a passage 30 which extends to a return tube 31. The tube 31 is threaded into the lower end of the casing 10 and a fuel supply tube

30 32 which is positioned in the center of the base 14, is also threaded into the lower end of the casing 10.

The fuel disc 11 is provided with spaced radially disposed notches 33 and, as shown in Fig. 4, the edge of the disc is beveled to correspond with the taper of the inner surface 28 of the casing 10 whereby the disc rests against the inner surface, as shown in Fig. 4.

The down draft flue 12, which is positioned in an opening 34 in the cover 19 of the housing is supported by an adjusting screw 35 that is threaded in a cross bar 36, and 40 with the lower end of the adjusting screw resting upon the upper surface of the disc 11 the elevation of the lower end of the down draft flue 12 is adjustable in relation to the upper edge of the burner casing. The cover 19 is provided with an opening 37 in which a cover plate 38 having a handle 39 is positioned.

The deflector 20 is connected by hinges 40 to a horizontal section 41 of a rod supported above the housing of the burner with arms 42 and 43. The opposite end of the deflector 20 rests upon a similar rod 44 which is also supported above the cover 19 with arms 45 similar to the arms 42 and 43. The cover 19 is secured to the housing with bolts or screws, as indicated by the numeral 46.

The end wall 18 of the burner housing is provided with an annular flange 47 that extends around an opening 48 and, as illustrated in Fig. 4, the end of the header 21 is positioned over the flange 47 whereby heat from the burner housing passes directly into the header.

The lower ends of the legs 24 and 25 that support the baffle 22 are secured by bolts 49 and 50 between flanges forming the ends of bands 51 and 52 which extend around the outer surface of the header 21.

The upper ends of the legs 24 and 25 are provided with hubs 53 and 54 in which the ends of the shaft 23 of the baffle 22 are clamped with hand screws 55 and 56 whereby the baffle may be clamped in adjusted positions as indicated by the dotted lines in Fig. 3. The legs 24 and 25 are provided with openings as indicated by the numeral 57 in which one end of the shaft 23 may be positioned when it is desired to adjust the baffle to an inclined position such as indicated by the dotted lines in Fig. 2. It will be noted that the ends of the shaft 23 extend beyond

the hubs 53 and 54 to provide sufficient length so that one end of the shaft may be held in one of the hubs with the opposite end in one of the openings 57.

The baffle 22 is also provided with a transversely disposed plate 58 which, with the baffle adjusted to the position of the dotted lines, sloping downwardly toward the burner housing, prevents the tobacco sliding from the baffle to the burner housing.

With the parts arranged in this manner the header 21 may extend from the burner housing to a remote point such as throughout the lower part of a tobacco barn or the like, or the header 21 may be attached to an elongated header as indicated by the numeral 59. The headers 21 and 59 are positioned in the form of a rectangle with portions thereof spaced from the side and one end of a tobacco barn and with the header extending from the housing around the cup-shaped burner element 10 to a stack or the like, the pull, resulting from the draft of the stack circulates air through the header 59, thereby drawing the air downwardly through the flue 12 whereby heated air is supplied to the burner in the cup-shaped casing 10. With the flue 12 surrounded by the flame of the burner air passing downwardly therethrough is heated to a comparatively high degree. The baffles 20 and 22 are adapted to be adjusted to deflect heated air to isolated points throughout the housing or barn or to substantially any point where tobacco in the barn is curing slowly.

The burner housing may be positioned at any suitable point in the tobacco barn or other enclosure and the burner is supplied with fuel by the pipe or tube 32, which may be provided with valves, such as the valve 60, shown in Fig. 3.

By this means heat may be supplied to an enclosure for curing tobacco and instead of passing directly upward

the heated air may be deflected to different points throughout the interior of the enclosure.

It will be understood that modifications within the scope of the appended claim may be made in the design and arrangement of the parts without departing from the spirit of the invention.

What is claimed is:

In a heater for tobacco curing barns, the combination which comprises an elongated burner housing, rectangular-shaped in cross section, a burner in the housing, a tube extended into the housing for supplying air of combustion to the burner, means for supplying fuel to the burner, vertically disposed arms extended upwardly from the burner housing, a shaft connecting upper ends of the arms at one end of the housing, a deflector carried by said shaft and positioned to rest upon upper ends of the arms at the opposite end of the housing whereby the deflector is adapted to be adjusted to an inclined position, a header extended from one end of the housing, bands providing clamps extended around the header, vertically disposed legs extended upwardly from the clamps, a longitudinally disposed shaft carried by upper ends of the legs, and a transversely disposed baffle carried by said shaft, said baffle being adapted to be adjusted to inclined positions both laterally and longitudinally.
